UNITED STATES PATENT OFFICE.

HENRY C. FRANK, OF NEW YORK, N. Y.

DESIGN FOR A CUFF-HOLDER.

SPECIFICATION forming part of Design No. 28,725, dated May 31, 1898.

Application filed April 8, 1898. Serial No. 678,960. Term of patent 14 years.

To all whom it may concern:

Be it known that I, HENRY C. FRANK, a citizen of the United States, and a resident of New York, in the county and State of New York, have invented and produced a new and original Design for Cuff-Holders, of which the following is a specification, reference being had to the accompanying drawings, forming a part thereof.

10 The leading feature of my design consists in a cuff-holder comprising a stock bifurcated at one end, each branch of the bifurcated end of the stock being bifurcated at its end.

15 In the accompanying drawings, Figure 1 is a plan view of the holder, and Fig. 2 is an end view.

The stock is denoted by A and the branches of its bifurcated end by a a' . The branches

of the bifurcated end of the branch a are denoted by b and of the branch a' by b' . 20

I have shown, as an additional feature of the design, the stock bent laterally, so that the planes of the branches a a' would meet at an angle if projected toward each other.

What I claim is—

The design for a cuff-holder, substantially as herein shown and described.

In testimony that I claim the foregoing as my invention I have signed my name, in presence of two witnesses, this 2d day of April, 25 1898.

HENRY C. FRANK.
